CABINET FOR ELECTRONIC EQUIPMENT

Bertram W. Sathmary, Asbury Park, Daniel Sinnott, Wanamassa, and James L. Schmidt, Red Bank, N.J., assignors to Electronic Associates, Inc., Long Branch, N.J., a corporation of New Jersey

Filed Dec. 18, 1964, Ser. No. 83,089

Term of patent 14 years

(Cl. D26—5)

FIG. 1

FIG. 2

FIG. 3

FIG. 1 is a front perspective view of a cabinet for electronic equipment showing our new design;

FIG. 2 is a right front perspective view thereof; and

FIG. 3 is a perspective view of the rear and right hand side thereof.

The top of the cabinet is plain and unornamented.

We claim:

The ornamental design for a cabinet for electronic equipment, substantially as shown and described.
